UNITED STATES PATENT OFFICE

115,013

DESIGN FOR A KNIFE RACK

Samuel Vallon, San Francisco, Calif.

Application March 4, 1939, Serial No. 83,352

Term of patent 7 years

To all whom it may concern:

Be it known that I, Samuel Vallon, a citizen of the United States of America, residing at San Francisco, in the county of San Francisco and State of California, have invented a new, original, and ornamental Design for a Knife Rack, of which the following is a specification, reference being had to the accompanying drawing, forming a part thereof.

Fig. 1 is a perspective view of a knife rack, showing my new design;

Fig. 2 is an edge view thereof; and

Fig. 3 is a top plan view thereof.

I claim:

The ornamental design for a knife rack, substantially as shown.

SAMUEL VALLON.
